CASING FOR A TELEPHONE BELL SET

Marco Zanuso, Milan, Italy, and Richard Sapper, Stuttgart-Degerloch, Germany, assignors to Italiania Telecomunicazioni Siemens S.p.A., Milan, Italy

Filed Aug. 8, 1966, Ser. No. 3,544

Claims priority, application Italy, Mar. 10, 1966

Term of patent 14 years

(Cl. D26—14)

FIG. 1 is a perspective view of a casing for a telephone bell set, showing our new design;

FIG. 2 is a side elevation thereof;

FIG. 3 is a top plan view thereof.

We claim:

The ornamental design for a casing for a telephone bell set, as shown.
